TRIS(PHENYL CHLOROETHYL)PHOSPHITE

John A. Pianfetti, South Charleston, W. Va., and Gennady M. Kosolapoff, Auburn, Ala., assignors to Food Machinery and Chemical Corporation, New York, N. Y., a corporation of Delaware

No Drawing. Application October 7, 1955
Serial No. 539,260

1 Claim. (Cl. 260—461)

This invention relates to a new composition of matter, 15 novel method of preparing same, and its use as a gasoline ignition control additive.

The need for improved gasolines has been spurred since the end of World War II by the automotive industry's race to produce more and more powerful internal combustion engines. To achieve this greater horsepower, engine manufacturers have steadily increased cylinder compression ratios to the point where they now average 7.5 to 1.

One of the factors necessary to achieve maximum operating efficiency from these high compression engines is that the ignition of the fuel-air mixture takes place at the moment of greatest compression.

As engines became more powerful, they have demanded higher octane fuel which could be manufactured only with an increase in the tetra-alkyl lead content. The use of these organic lead compounds in gasoline leads to the formation, during combustion, of lead salts and salts of other metals which catalyze the oxidation of carbonaceous residues from fuel and oil and lower the ignition temperature of the carbon residues so that there is created glowing particles that ignite the fuel-air charge prematurely. The ignited deposits act as hot spots within the chamber and pre-ignite the fuel mixture before it reaches the point of greatest compression.

Heretofore, it has been the practice of the art to add to fuels containing organic lead compounds, a halohydrocarbon for the purpose of converting the lead into lead halides volatile at the combustion temperature and which would be swept out with the exhaust gases. These compounds are known as scavengers.

In actual practice, however, the formation of lead oxyhalides and lead oxides as well as the volatile lead halides cannot be avoided and deposits of lead compounds are found in the combustion chamber even when such scavengers are employed.

It is an object of the instant invention to provide a new composition of matter which may be employed as a gasoline additive. It is another object of this invention to provide a new composition of matter which will aid in the suppression of the pre-ignition characteristics of the fuel-air mixture. It is a further object of this invention to provide a novel means for preparing this new composition of matter. Further objects will appear as a description of this invention unfolds.

We have discovered a certain organophosphorus compound having properties which renders it suitable for use as a pre-ignition control additive. It has been found that the defect of pre-ignition arising from the use of conventional leaded gasolines can be avoided by the use of this compound.

The organo-phosphorus compound of this invention appears to function by converting the lead present in the fuel into a lead compound having a very low catalytic effect in reducing the ignition temperature of the carbon deposits within the combustion chamber as compared to the lead compounds that form in the combustion cham-

2

ber, absent the organo-phosphorous compounds of this invention. Thus, an increase in the ignition temperature of the cylinder deposit would likewise decrease the tendency of the deposit to pre-ignite the fuel-air mixture.

5 The terms, ignition temperature and glow point, are meant to be synonymous for the purposes of this specification unless a contrary intention is shown.

It is reported by those skilled in the art, that the glow point of combustion chamber deposits is directly 10 related to the number of pre-ignitions occurring in the chamber.

The organo-phosphorus compound which we have discovered as suitable for use in accordance with this invention is tris (phenyl chloroethyl) phosphite. The structural formula for said compound is as shown below:

The compound of the instant invention was prepared 20 in a novel manner. The novel manner of preparation involved the reaction between styrene oxide or phenyl oxirane and phosphorus trichloride. The details of the reaction are set forth in Example I.

The term oxirane is used to designate the grouping

25

hence

30

is known as phenyl oxirane.

EXAMPLE I

35 The apparatus used for this run was a three-necked flask fitted with a stirrer, thermowell, reflux condenser and a calibrated addition funnel.

The flask was charged with 113 parts of phosphorus trichloride and from the calibrated addition funnel was 40 added 310 parts of phenyl oxirane (styrene oxide). The oxirane was added over a period of an hour while maintaining the temperature of the reaction mass at about 25° C.

Upon completing the addition of the oxirane, the pressure 45 in the system was reduced for a short interval of time to 2 mm. Hg in order to remove any traces of oxirane.

The product, tris(phenyl chloroethyl) phosphite obtained in near quantitative yield had a specific gravity of 1.255 35/4° C. and a refractive index of 1.5713 D/25° C.

Calculated for $C_{24}H_{24}O_3PCl_3$, P=6.2%, Cl=21.4%. Found P=5.9%, Cl=22.2%.

Preliminary testing of this compound involved the 55 common gasoline acceptance tests including: solubility of compound in gasoline, water tolerance, gum formation and copper corrosion.

The first test, gasoline solubility, was conducted to determine at least qualitatively whether the organophosphorus compound was soluble in gasoline. This determination was made by measuring the light transmittancy of the gasoline both with and without the addition of the organophosphorus compound.

Solution which contained 0.03 volume percent of the 65 phosphorus compound was prepared by adding 0.03 ml. of the compound to 100 ml. of a premium gasoline. After a short shaking and standing period the solution was transferred to an optical cell and the light transmittance of the solution measured. This value was compared to the value for the premium gasoline which did not contain an additive.

A decrease in the light transmittance of the base fuel

of 1% or more indicates that the additive is sufficiently soluble for the purpose of this invention.

The water tolerance was determined by following the procedure detailed in ASTM D1094-52.

The gum formation was determined by employing the copper dish method set forth in ASTM D910-52T, Section 9J.

The copper corrosion test was conducted in accordance with the instructions stated in ASTM D130-53T.

The results of the above tests are tabulated in Table I. The compounds, tris(phenyl chloroethyl) phosphite and tricresyl phosphate are represented by the abbreviations TPCEP and TCP in Tables I and II.

The inclusion of the compound, tricresyl phosphate, in the tables of the instant specification is for the purpose of comparing the compounds of the instant invention with that of a known gasoline pre-ignition additive.

Table I

Additive	Solubility	Water Tolerance	Gum Formation, mg./100 ml.	Copper Corrosion ASTM Index	
				Additive, 0.03%	Conc., 0.015%
TPCEP	OK	OK	28	0	-----
TCP	-----	-----	33	0	-----

An analysis of Table I shows the compound of the instant invention to be compatible with gasoline in so far as the common acceptance tests are concerned.

As mentioned previously, a definite correlation exists between the glow point of the cylinder residues and the number of pre-ignitions.

Set forth below is the method employed in determining the glow point of the compound of this invention.

A synthetic engine deposit which contained 38.3% lead sulfate, 33.1% lead oxide, 7.7% lead chloride, 5.9% lead bromide and 15.0% carbon black was prepared by adding the approximate amounts of the several compounds together and mixing in a mortar and pestle. To a Pyrex Petri dish, $\frac{1}{10}$ in. high and $5\frac{1}{2}$ in. in diameter was added 0.40 g. $\pm$ 0.1 g. of the synthetic deposit. Over this was burned in 100 ml. portions, gasoline which contained 0.03 volume percent of the several organophosphorus compounds tested. The amount of additive used was dependent on the phosphorus content of the organophosphorus compound. Enough phosphorus was used to theoretically convert all the lead in the synthetic deposit to lead phosphate. Air was introduced into the gasoline during the burning operation at 2500 cc. a minute in an attempt to convert some of the carbon given off during burning to oxides of carbon. An iron-constantin thermocouple was also placed in the burning fuel in order to obtain some idea as to the temperatures that occurred in the burning step. The majority of the gasoline burned between 150-200° C. and the end gases, approximately 5-10%, burned between 350 and 450° C. After burning was finished the deposit was scraped from the bottom and the inside wall of the dish and this material then mixed in a mortar and pestle. A glow point determination was then made on the treated deposit.

The apparatus for a glow point determination consisted of a copper block, 3 in. in length by 2 in. in diameter. A $\frac{1}{4}$ in. wide collar was at one end of the block. Two vertical holes, 2.5 in. long and 10 cm. in diameter were drilled in the block. The block was heated by a 9 in. by 8 in. electric heating shell which was encased in aluminum. The deposit was placed in a Pyrex heating boat which was 1 in. tall and 10 cm. in diameter. Air was metered through a rotameter and jetted onto the deposit through a steel hypodermic needle. The needle extended $2\frac{1}{2}$ inches inside the drilled hole. The temperature was found by means of a Chromel-Alumel thermocouple, which extended into the deposit.

In a typical experiment 0.2 g. of deposit was placed in a Pyrex boat and packed lightly into the Pyrex container. The thermocouple was placed in the deposit and air introduced at the rate of 200 cc./min. The variac which controlled the heating rate was set at 80 volts and was kept at this reading through the experiment. Temperature readings were taken every 10 minutes until 40 minutes had elapsed. After 40 minutes readings were taken in 0.5 to 1.0 minute intervals and the degree centigrade resulting from a sudden increase in temperature was taken as the glow point of the deposit.

The results of the above determination are recorded in Table II.

Table II

15	Additive:	Average glow point, ° C.
TPCEP	-----	350
TCP	-----	327
None	-----	309

20 The novel additive of the present invention may be used in conjunction with the previously mentioned halohydrocarbons.

25 Examples of these halohydrocarbons are ethylene dibromide or dichloride, acetylene tetrabromide, 2,2,3-trichlorobutane, 2-chloro-2,3-dibromobutane, and the dibromomtoluenes. Mixtures of these halohydrocarbons, such as a mixture of ethylene dibromide and ethylene dichloride, may also be used. In general halohydrocarbons having a vapor pressure in the range of 0.1 mm. to 100 mm. mercury at 50° C. are capable of being used. It is desirable that the combined organo-phosphorus and halohydrocarbons contain not more than about 90% by weight of the halohydrocarbons.

30 In general, the quantity of additives required in the fuel is that necessary to convert (theoretically) all the lead present as tetra-alkyl lead, into the corresponding lead halide and lead salt of the phosphite. Such a quantity is referred to as "1 theory." Greater or smaller quantities may be employed in some circumstances depending upon the particular components of the fuel and the type of engine in which it is intended to be used. In fact, one of the merits of the present invention is that it allows greater variations in the quantity of additive employed than is permissible when a halohydrocarbon is used as the sole additive. Even small excesses of halohydrocarbon additives are detrimental in such circumstances whereas with the additives of this invention a substantial excess can be tolerated without adverse results. The preferred range of total additive content of the fuel is 50 from 0.9 to 1.2 theories.

35 Both the fuels and the composition suitable for addition to fuels provided by this invention may advantageously contain further compounds known to exert a stabilizing and/or anti-oxidizing effect on hydrocarbons of the gasoline boiling range. In this connection, 2,4-dimethyl-6-tertiary butyl phenol is a particularly useful additive, other compounds such as hydroquinone, 2,6-di-tertiary-butyl-4-methyl, phenol, N-phenyl- α -naphthylamine and N,N'-diethyl-p-phenylenediamine may be employed.

40 60 While the invention has been described with special reference to tetra-ethyl lead, it can be applied equally well to other tetra-alkyl lead anti-knock agents, such as ethyl-trimethyl lead, diethyl-dimethyl lead, tri-ethylmethyl lead and tetramethyl lead.

45 65 The fuels of this invention may be compounded by simple mixing of the ingredients in any order. Thus the organo-phosphorus additive may be added to a leaded gasoline which already contains a halohydrocarbon additive. Alternatively, the organophosphorus may be incorporated in a tetra-alkyl lead fluid containing a halohydrocarbon additive and the whole composition blended into the fuel. Again the organo-phosphorus additive may be added to an unleaded gasoline and the tetra-alkyl lead fluid containing a halohydrocarbon scavenger added 70 75 subsequently.

Pursuant to the requirements of the patent statutes, the principle of this invention has been explained, and exemplified in a manner so that it can be readily practiced by those skilled in the art, such exemplification including what is considered to represent the best embodiment of the invention. However, it should be clearly understood that, within the scope of the appended claim, the invention may be practiced by those skilled in the art, and having the benefit of this disclosure, otherwise than as specifically described and exemplified herein.

5

That which is claimed as patentably novel is:
A composition of matter, tris(phenyl chloroethyl) phosphite.
